UNITED STATES PATENT OFFICE.

JAMES W. TUCKER, OF ARGENTA, ARKANSAS.

JACK.

1,157,461.

Specification of Letters Patent.

Patented Oct. 19, 1915.

Application filed January 25, 1915. Serial No. 4,279.

To all whom it may concern:

Be it known that I, JAMES W. TUCKER, a citizen of the United States, residing at Argenta, in the county of Pulaski and State 5 of Arkansas, have invented certain new and useful Improvements in Jacks; and I do hereby declare the following to be a full, clear, and exact description of the invention, such as will enable others skilled in the art 10 to which it appertains to make and use the same.

My invention relates to improvements in jacks and has for its primary object to provide a simple and effective jack that is particularly 15 designed for railroad work for the purpose of separating journal boxes from their axles so that the brasses may be moved and replaced.

Another object of my invention is to provide 20 a jack which comprises a pair of adjusting screws arranged to move correspondingly and provided with simple, easily operable and effective adjusting means, also bearing members to engage the objects to 25 be separated or moved relative to one another.

Another object is to provide simple and effective means for engaging the wheels of the car in such manner that the jack may be 30 operated without liability of its slipping relative to the wheel.

Another object is to generally improve and simplify jacks of the character described so as to render them more practical, and 35 simple as to construction without increasing the cost of manufacture thereof.

The above and additional objects are accomplished by such means as are illustrated in the accompanying drawings, described in 40 the following specification and then more particularly pointed out in the claims.

With reference to the drawings, wherein I have illustrated the preferred embodiment 45 of my invention as it is reduced to practice, and throughout the several views of which similar reference numerals designate corresponding parts, Figure 1 is a side elevation of my improved jack, Fig. 2 is a top plan view and Fig. 3 is a sectional view showing 50 it mounted on a car wheel and ready for operation.

Referring to the drawings by characters of reference, 1 and 2, designate upper and lower adjusting screws that are oppositely

threaded and supported by a rotatable 55 frame 3, said frame 3 being of skeleton construction.

Carried on the outer end of the upper adjusting screw 1 is an object engaging plate 4 that is secured centrally to said screw 1 60 and disposed in a horizontal plane for engagement with one of the objects to be moved or lifted.

Secured upon the lower or outer end of the lower adjusting screw is a segmental or 65 arcuate wheel tread engaging plate 5. This plate 5 is secured centrally of its ends to said screw 2 and is designed for engagement with a car wheel or other object to be moved or which is to act as a support for the jack. 70

Secured upon the upper face of the plate 5 at the ends thereof are flange engaging hooks 6. Each of these hooks comprises a relatively flat and straight shank portion 7 that is provided at its free end with right 75 angularly directed flanges 8 which are disposed in opposite directions and arranged to engage the inner faces of the flanges of car wheels. At one end of the shank 7 is formed a barrel 9 to receive a pivot or hinge 80 pin 10. U-shaped brackets 11 are secured to the ends of the plate 5 on the upper face thereof and support the pin 10 and hooks 6 in such manner that the hooks 6 may be 85 swung from one side of the plate to the other. The hooks 6 are preferably formed 90 of resilient material and of a single piece thereof and are provided by doubling the single piece to form the shank 7 and then direct the ends of the double portion outwardly to provide the flanges 8. The frame 3 consists of a rectangular body portion 12 which has alined openings in its ends to receive the screws 1 and 2. Extending from the ends of the rectangular body portion 12 95 are reduced frame extensions 13 which have apertures extending therethrough alining with the apertures in the ends of the frame portion 12 to receive the screws 1 and 2. The frame is to be rotated to effect the adjustment of the screws 1 and 2. An operating handle 14 is inserted transversely 100 through the sides of the body portion 12 of the frame 3 and projects from said sides so that it may be readily grasped to effect rotation of the frame.

In use when it is desired to lift a journal box from the axle in order to have access to

the brass in the box, the plate 5 is placed upon the tread portion of a car wheel and the hooks 6 arranged so as to engage the inner face of the flange of the wheel as shown in Fig. 3. By rotating the handle 6, the frame is caused to rotate and move the screws 1 and 2 outwardly. Prior to the adjustment of the screws, the plate 4 is placed in engagement with the under face of 10 the floor of a car and it will be seen that upon adjustment of the screws the journal box will be lifted from bearing engagement with the axle. In having the hooks movable from one side of the plate 5 to the other, the 15 device is adapted for use in connection with the wheels on either side of a car and when the hooks are in position relative movement of the jack to the wheels is obviated.

While I have shown my jack used in connection with the repair of journal boxes it 20 is to be understood that it may be used for various other purposes for supporting objects, etc.

With reference to the foregoing description and accompanying drawings it will be observed that I have provided an extremely light and quickly operable expansion jack which may be used to great advantage in railroad work for spacing objects relative to 30 each other or for lifting purposes.

In practice, I have found that the form of my invention, illustrated in the drawings and referred to in the above description, as the preferred embodiment, is the most 35 efficient and practical; yet realizing that the conditions concurrent with the adoption of my device will necessarily vary, I desire to emphasize the fact that various minor changes in details of construction, proportion and arrangement of parts may be resorted to, when required, without sacrificing any of the advantages of my invention, as 40 claimed.

What is claimed is:—

45 1. A jack of the class described comprising an adjusting screw and a wheel tread engaging plate having a segmental or concaved face to fit the tread of a wheel, means carried by the plate for engaging the wheel

to retain the said plate on the tread and adjusting means co-operating with the screw. 50

2. A jack comprising an adjusting screw, and a segmental wheel tread engaging plate on said screw, pivoted hooks for engagement with the flange of the wheel carried on said 55 plate to adjust said screw.

3. A jack comprising a rotatable frame, oppositely threaded adjusting screws movably carried by the frame, an object engaging plate carried on the outer end of one of the screws, an arcuate car wheel tread engaging plate carried on the outer end of the other of the screws and pivoted flange engaging hooks carried by said plate. 60

4. A jack comprising a rotatable frame, 65 oppositely threaded adjusting screws movably carried by the frame, an object engaging plate carried on the outer end of one of the screws, an arcuate car wheel tread engaging plate carried on the outer end of the 70 other of the screws, pivoted flange engaging hooks carried by said plate, and means to rotate said frame.

5. A jack comprising a skeleton frame, 75 adjusting screws carried by the frame, said frame to be rotated to effect adjustment of the screws, said screws arranged to move outwardly from the frame in the opposite direction, an object engaging member carried upon the outer end of one of the screws, a 80 wheel engaging plate carried upon the other of the screws and flange engaging members carried upon said plate.

6. A jack comprising a rotatable frame, 85 upper and lower screws oppositely threaded into the frame and a wheel engaging plate connected with the lower screw and having a concaved face to fit the tread of a wheel, said plate being also provided with means for engaging a wheel to retain it on the 90 tread.

In testimony whereof I affix my signature in presence of two witnesses.

JAMES W. TUCKER.
